UNITED STATES PATENT OFFICE

2,452,676

ADJUSTABLE INDUCTOR

Edgar O'Brien, Chicago, Ill., assignor, by mesne assignments, to Belmont Radio Corporation, Chicago, Ill., a corporation of Illinois

Application August 12, 1944, Serial No. 549,275

2 Claims. (Cl. 171—242)

1

This invention relates to adjustable inductors and, while it is of general application, it is particularly suitable for embodiment in an inductor used as a continuously adjustable tuning element of a high-frequency tunable circuit, such as the tank circuit of a high-frequency oscillator.

Continuously adjustable inductors have wide application as adjustable tuning elements in high-frequency and ultra-high-frequency circuits. A great many continuously adjustable inductors have heretofore been proposed, one of the common forms comprising a helical coil mounted on a rotatable insulation form and a sliding contact engaging the conductor of the helical winding and movable longitudinally by such engagement. The circuit connections to the inductor winding have generally been made by slip rings, while the connection to an intermediate point of the winding has been made through the sliding contact engaging the winding and by the engagement of the contact with its conductive slide. Thus, there has been a total of four sliding or moving contacts found in the usual construction. Furthermore, in such prior art inductors, for convenience in adjustment and making circuit connections, the structure has been open, with the result that the contacts have been exposed, thereby collecting dirt and dust in use. As a result, such continuously adjustable inductors of the prior art have tended to be very noisy electrically in operation. Furthermore, when such an inductor is used as a coupling element, it is mechanically and electrically difficult to mount a secondary winding with an accurately predetermined amount of coupling to the adjustable winding.

It is an object of the invention, therefore, to provide a new and improved adjustable inductor which overcomes one or more of the above-named disadvantages and limitations of the adjustable inductors of the prior art.

It is another object of the invention to provide a new and improved adjustable inductor which includes a minimum number of movable contacts and therefore is exceptionally quiet electrically in operation.

It is another object of the invention to provide a new and improved adjustable inductor in which the moving contacts are completely enclosed within the structure itself, thereby avoiding the effects of accumulated dirt on the contacts.

It is another object of the invention to provide a new and improved adjustable inductor suitable for use as a coupling device by means of which a secondary winding may be readily cou-

2

pled thereto with an accurately predetermined mutual inductance.

In accordance with the invention, an enclosed adjustable inductor comprises a tubular form of insulation material, a helical inductor winding disposed on the inside wall of the form and an internal contact element engaging the winding. The inductor also includes means for moving the contact element in a helical path while maintaining a sliding engagement with the winding and a pair of terminals connected to electrically spaced points of the inductor.

In a preferred form of the invention, the internal contact element and its means for moving it in a helical path comprise a conductive rod disposed centrally in the form and having a helical groove of the same pitch as the winding, a rotatable longitudinal guide means journaled on the rod, a contact member slidably supported on the guide means and including a contact element engaging the winding and a second contact element engaging the groove on the conductive rod and electrically connected to the first contact, together with means, such as a manually operable knob, for rotating the guide means about the rod to cause the contact element to move in its helical path.

For a better understanding of the invention, together with other and further objects thereof, reference is had to the following description taken in connection with the accompanying drawings while its scope will be pointed out in the appended claims.

Referring now to the drawings, Fig. 1 is a longitudinal sectional view and Fig. 2 is a cross sectional view along the line 2—2 of Fig. 1 of a continuously adjustable inductor embodying the invention; Fig. 3 is a detail perspective view of a movable contact structure embodied in the apparatus of Figs. 1 and 2; while Fig. 4 is a schematic representation of an application of the adjustable inductor of the invention to a tunable antenna circuit of a wave-signal translating apparatus.

Referring now to Figs. 1 and 2 of the drawings, there is illustrated an enclosed, continuously adjustable inductor embodying the invention. This inductor comprises a tubular form 10 of insulation material, preferably a thermosetting plastic material, such as materials commercially available as "Bakelite," "Lucite" or "Vinylite," the latter two being transparent, thereby permitting inspection of the interior of the apparatus. The form 10 is provided with an internal helical groove 10a on its inside wall in which is mounted

a helical inductor 11, which may be preformed and either threaded into the groove or contracted and sprung into the groove.

The inductor also includes an internal contact element engaging the inductor winding together with means for moving the contact element in a helical path while maintaining a sliding engagement with the winding. This internal contact element and its moving means are constructed in the form of a conductive rod 12 disposed centrally in form 10 and having formed thereon a helical groove 12a of the same pitch as the helical inductor winding 11. These means also include a rotatable longitudinal guide means disposed in the form 10 and preferably journaled on the rod 12, preferably consisting of a pair of parallel rods 13 and 14 secured at their ends to a pair of crosspieces 15 and 16 by screws, rivets, or the like. Secured to the crosspiece 15 by rivets, screws, or the like is a flanged shaft or hub 17, on the outer end of which is mounted means for rotating the guide means, such as a knob 18.

A contact member 19, Figs. 2 and 3, is slidably supported on the guide means; for example, it may comprise a disk-like element 19, provided with a pair of holes 19a sliding on the rods 13 and 14. The contact member 19 includes a contact element 19c, including a grooved projection 19d adapted to engage the conductor of the helical winding 11. The contact member also includes a second contact element 19e provided with a pin-like projection 19f engaging the groove 12a of the rod 12. The contact elements 19c and 19d are biased into engagement with the winding 11 and the rod 12 by means of a double reversely bent leaf-spring 19g. As indicated more clearly in Fig. 3, the member 19 is formed with a deep slot 19b, the inner end of which slides on rod 12, while the spring 19g is in turn provided with edge slots 19h engaging the sides of the slot 19b so that the contact elements 19c and 19e are permitted limited radial movements within the slot 19b of the member 19 to maintain the desired contact pressures. The spring 19g is of conductive material, for example, spring brass or phosphor bronze, and electrically interconnects the contact elements 19c and 19e which may be secured thereto by riveting, welding, or the like.

The inductor structure also includes a pair of plates of insulation material secured to and closing the ends of the form 10 and supporting the contact member 19 and its associated contact elements and the contact-element moving means. Specifically, each of the end plates is preferably formed of a thermosetting plastic resin, such as "Bakelite," one of the plates 20 being secured to one end of the form 10 by means of screws 20a and supporting the grooved rod 12 as by engaging a shoulder 12b formed on the rod 12 which is locked to the plate 20 by means of a pair of lock nuts 12c and washers 12d. The rod 12 is thus rigidly supported from the end plate 20 and thus from the form 10 only at one end. The other end plate 21 is similarly secured to form 10 by screws 21a and includes a sleeve bearing or bushing 21b in which the operating hub or shaft 17 of the guide means is journaled. The hub 17 also includes a recess 17a which is rotatably mounted or journaled on an end 12e of the rod 12 of reduced section. Thus, with the shaft 17 rigidly mounted in end plate 20, the shaft 17 journaled in end plate 21 and journaled on the end 12e of rod 12, and with the crosspiece 16

of the guide means slidably and rotatably mounted on the rod 12, the whole structure is secured together while permitting rotation of the guide means 13, 14, 15, 16 and 17 within the form 10 and about the rod 12.

A secondary winding 22 of any desired number of turns is disposed about the form 10, its terminals being brought out to a pair of connection lugs 23 mounted on the end plate 21. The inductor may be provided with any number of electrically spaced terminals, such as a pair of terminals 24a and 24b, it being apparent that with the stationary form 10 and winding 11, the addition of intermediate terminals does not in any way complicate the construction or increase the number of movable contacts required. For example, the terminal 24a may be connected to a fixed point near one end of the winding 11 by means of a strap or loop connection 24c suitably soldered or otherwise bonded to the terminal 24a and to the winding 11. The other terminal 24b is connected by means of a conductive strap 25 to the fixed conductive rod 12 and thus to the contact element 19d mounted in contact member 19 and engaging the winding 11. The terminal 24b may, if desired, also be connected to a fixed point near the other end of the winding 11 as by means of a loop or strap connection 24d also soldered or otherwise bonded to the terminal 24b and the winding 11. With this connection, the portion of the inductor winding between the contact element 19d and the end to which the terminal 24b is connected is effectively short-circuited. However, it will be understood that the electrical connections to any of the fixed points on the inductor winding 11 and to the adjustable contact element 19d may be made in accordance with the circuit requirements of the particular apparatus of which the inductor forms a part. A crossplate 26 of insulation material is secured to the end plates 20 and 21 by means of screws 26a and serves to increase the rigidity of the structure and to function as a terminal board or strip for the terminals 24a and 24b.

The operation of the adjustable inductor will be apparent from the foregoing description. In brief, adjustment of the operating knob 18 is effective to rotate the guide mechanism 13, 14, 15, 16 carrying the contact member 19. Due to the engagement of the pin 19f of the contact element 19e in the groove of the rod 12, which has the same pitch as the winding 11, rotation of the guide means causes rotation of the contact element 19d in engagement with the winding 11 and a simultaneous co-axial movement required to maintain the contact 19d in engagement with the winding 11. That is, the contact element 19d is positively driven axially so that it does not rely on its mere frictional engagement with the winding 11. This feature enables the mechanism to operate reliablyly even under adverse climatic conditions, such as icing frequently encountered in aircraft apparatus at high altitudes. At the same time an electrical circuit is completed from the contact element 19d through the spring 19g, the contact element 19e, rod 12 and the conductive strap 25 to the terminal 24b. Thus, there appears between the terminals 24a and 24b a continuously adjustable portion of the inductor winding 11.

It will be noted that between the terminals 24a and 24b there are only two slidably or otherwise movable contacts; namely, the contact between the element 19d and the winding 11 and the con-

tact between the element 19e and the rod 12. Furthermore, it will be seen that these contacts are inside of a completely enclosed, dustproof housing formed by the winding form 10 and the end plates alone and without the addition of any other housing means. As a result, the moving contacts are kept clean and free from dirt which would otherwise tend to impair the contacts and to make them electrically noisy. Also, it will be seen that a secondary winding 22 of any desired number of turns and configurations may be readily disposed on the outside of the form 10 so that its self-inductance and its mutual inductance with the winding 11 can be readily predetermined and adjusted.

Referring now to Fig. 4, there is represented schematically an application of the adjustable inductor of the invention to the tunable antenna circuit of a wave-signal translating apparatus. The inductor 30 is effective to tune the circuit 30, constructed in accordance with the invention and provided with an adjustable contact 30a for short-circuiting a selected portion of the inductor winding. The inductor 30 is connected across a tuning condenser 31 which may be either fixed or adjustable, as indicated. The tuning circuit is connected between an antenna 32 and ground. The inductor 30 is provided with a secondary winding 30b which is connected to a wave-signal translating apparatus which may be either a receiver or transmitter, although the invention is particularly suitable for use in tunable circuits of a high-frequency radio transmitter. It will be apparent that adjustment of the contact 30a of the inductor 30 is effective to tune the circuit 30, 31 over a desired frequency range. At the same time, the proportioning and positioning of the secondary winding 30b may be so selected that the coupling between the winding 30 and the winding 30b may be caused to vary in a pre-selected manner as the inductor 30 is adjusted over its operating range, thus to control the sensitivity and selectivity characteristics of the selector 30, 31.

While there has been described what is at present considered to be the preferred embodiment of the invention, it will be apparent to those skilled in the art that various changes and modifications may be made therein without departing from the spirit or scope of the invention.

What is claimed as new is:

1. An adjustable inductor comprising a tubular form of insulation material, a helical inductor winding disposed on the inside wall of said form, a conductive rod disposed centrally in said form and having a helical groove of the same pitch as said winding, an internal contact member including a first contact element electrically engaging said winding and a second contact element engaging said groove, spring means biasing said first and second contact elements into engagement with said winding and groove respectively and electrically interconnecting said contact elements, means for rotating said member about said rod to cause said first contact element to move in a helical path while maintaining a sliding engagement with said winding, and a pair of terminals connected to electrically spaced points of said inductor, one of said terminals being connected to said rod, whereby the circuit between said terminals includes only two sliding contacts.
2. An adjustable inductor comprising, a tubular form of insulation material, a helical inductor winding disposed on the inside wall of said form, an internal contact element engaging said winding, means for moving said contact element in a helical path while maintaining a sliding engagement with said winding, an elongated fixed contact element, a second contact element having a continuous conductive connection with said first-named contact element and a sliding engagement with said fixed contact element, and a pair of terminals connected to electrically spaced points of said inductor, one of said terminals being connected to said fixed contact element, whereby the circuit between said terminals includes only two sliding contacts.
